ABSTRACT

Contact printing apparatus for electrostatic pinning of sheets to each other and in abutment against a transparent plate of copyboard preparatory to exposing the electrostatically laminated sheets to light. The system includes a lid having a conductive pad of resilient, compressively-yielding material which is adapted to be pressed into contact with the laminate and grounded while a D.C. high voltage is applied to a conductive coating on the undersurface of the transparent plate. The built-in grounding of the conductive pad coupled with its resilience greatly increases the electrostatic pulling power by serving as a ground reference.

CONTACT PRINTING APPARATUS WITH ELECTROSTATIC HOLD-DOWN

This invention relates to a contact printing apparatus and more particularly relates to an electrostatic copy-board in which a sheet of photosensitive paper or film in contact with a negative is electrostatically laminated to the surface of a transparent plate preparatory to exposure to light transmitted thereupon from the opposite side of the transparent plate.

In contact printing, one or more sheets of photosensitive material are successively exposed to light through a negative or several negatives in abutment with the photosensitive sheet. During the contact printing operation, it is essential that the photosensitive sheet and the negatives be in intimate face-to-face contact with each other while at the same time allowing the various sheets to be manipulated with respect to each other in order to enable certain indicia thereon to register.

In the past, electrostatic hold-down and clamping systems have been utilized as a convenient means for pinning the sheets together and in abutment with an underlying surface. However, one of the problems encountered in electrostatically pinning film, especially heavy gauge stock, to another sheet has been a tendency for one or both members of the laminate to curl and produce wrinkles, such conditions causing poor registration and striations in the printed component.

The present contact printing apparatus employs a transparent plate, one surface of which has a transparent conductive electrode having a D.C. high voltage applied thereto. The photosensitive film and negatives are laid in face-to-face abutment with each other in contact with the non-coated surface of the transparent plate, the outermost surface of the laminate being contacted by ground to provide a conductive path to the low side of the D.C. high voltage. In this manner, opposite charges are produced at the opposing surfaces of each laminate interface and at the interface with the non-coated surface of the transparent plate, so as to cause the surfaces to be electrostatically adhered to each other. Light rays are then directed through the transparent plate to expose the photosensitive portion of the sheet which is not masked by the opaque portion of the negatives. In former systems, a ground applicator is rubbed or rolled over the outer surface of the laminate, providing the ground contact necessary to produce the electrostatic charges at the various interfaces. The contact is momentary and at different areas at different times.

In the present invention, a conductive pad of compressively yielding material is mounted upon the under-surface of a cover which is pressed down upon the transparent plate and on the laminate pinned thereto. The conductive pad is connected to ground, and it remains in position during the course of the operation. Thus the pad serves as a constant and continuous ground reference to enhance the pulling power of the electrostatic pinning system and to permit replacement of charges lost by leakage from the system. The pressure of the pad, moreover, is uniform and continuous over the entire area of the laminate, bringing the charges at the various interfaces into the proximity which is required for the electrostatic pinning forces to develop maximally over the entire area. The fact that the pad is grounded also causes the electrostatic forces to draw the resilient pad downward in still tighter

contact. The pressure, the grounding and the resilience of the pad and the electrostatic charges are all interrelated and work together to synergistically reinforce the electrostatic attractive forces and to maintain them at maximum levels, so as to assure intimate contact between sheets of the laminate and between laminate and transparent plate without curls and wrinkles.

It is therefore an object of this invention to provide a contact printing apparatus in which sheets of material, such as photosensitive film and negatives, can be electrostatically pinned to each other in intimate face-to-face contact with a transparent plate without curls or wrinkles preparatory to being exposed to light directed through the transparent plate.

Another object of this invention is to provide a contact printing apparatus in which electrostatic adhesion of the pinned together members is assured even after repeated manipulations.

Still another object of this invention is to provide a contact printing apparatus in which electrostatic pinning forces are reinforced synergistically by physical compressive forces.

Still another object of this invention is to provide a contact printing apparatus in which electrostatic pinning forces are maintained at maximum level.

Other objects of this invention are to provide an improved device of the character described which is easily and economically produced, sturdy in construction and highly efficient and effective in operation.

With the above and related objects in view, this invention consists of the details of construction and combination of parts as will be more fully understood from the following detailed description when read in conjunction with the accompanying drawing in which:

The FIGURE is a perspective view, and partly broken away in section, of an electrostatic contact printing apparatus embodying this invention.

Referring now in greater detail to the drawing in which similar reference characters refer to similar parts, the contact printing apparatus of the instant invention comprises a base or plaque portion, generally designated as A, and a cover B movable with respect thereto for electrostatically pinning therebetween a photosensitive sheet and mask laminate preparatory to exposure to light.

The base or plaque portion A includes a transparent plate 12, of glass for example, which is supported within a frame or cabinet 14. Substantially the entire lower surface of the transparent plate 12 is coated with an electrically conductive material, such as an evaporative film of gold, silver, copper or the like, to define a transparent electrode 16 whose thickness is in the range of a wave length of light. The transparent electrode 16 is connected by way of a lead 18 and a switch 20 to a high voltage D.C. generator C which is capable of applying from 2,500 to 20,000 volts D.C. (positive or negative) to the undersurface of the transparent plate 12. A series of lamps 22 are mounted on a shelf 24 within the cabinet 14 and when coupled to an electrical power source by way of a switch or timer 26 on the front of the cabinet direct rays of light through the coating 16 and the transparent plate 12 to permit contact printing of photosensitive film 28 in abutment with a negative or mask 30, both of which are electrostatically pinned in face-to-face contact with each and to the non-coated upper face of the plate 12.

The cover B includes a lid portion 32 made of a rigid material such as wood, metal or plastic, to the under surface of which is secured a resilient pad 34 having electroconductive characteristics. The pad 34 is preferably an elastomeric sponge material which is impregnated with a conductive filler, such as carbon or fine metallic powder. The lid 32 is pivotally secured to the back of the cabinet 14 by hinges 35 and balanced by springs (not shown) to enable movement toward and away from the transparent plate 12. In this manner, the cover B may be pressed down upon the laminated sheets 28 and 30 against the plaque portion A and locked down in light tight disposition thereover by means of latch 36. The conductive pad 34 is connected by an internal lead 38 to ground whereby a conductive path is established back to the low side of the high voltage generator C. When the cover B is pressed down and locked upon the plaque portion A, the resilient pad 34 presses the laminated film 28 and negative 30 into intimate physical contact with the transparent plate 12 so as to distribute the physical pressure uniformly thereupon while the electrostatic charges transported via the conductive pad 34 synergistically reinforces such physical pressure.

In order to electrostatically pin sheets to the surface 25 of copyboard, the D.C. high voltage from the generator C is applied to the transparent electrode 16 by closing switch 20. Negative 30 is laid upon the upper surface of plate 12 and a grounding applicator or roller (not shown) is brushed over the top surface of the negative 30. By virtue of the conductive path for electrostatic charges being established between the upper surface of negative 30 and the low side of the high voltage generator C, charges of opposite polarity will be developed on the opposing surfaces of the negative 30 and the transparent plate 12 so as to effect electrostatic adhesion of the negative to the plaque face. The film 28 is then laid upon the negative 30 which is pinned electrostatically to the upper surface of the transparent plate 12 and slidably manipulated on the negative until properly oriented. When registration of the film 28 on negative 30 has been effected, the grounding applicator is now brushed over the upper surface of the film sheet 28 to again define a conductive path for electrostatic charges from the film to the ground side of the high voltage 45 power supply C so as to cause charges of opposite polarity to be constituted on the opposed adjacent faces of the film 28 and the negative 30. The film 28 and the underlying negative 30 will now be tightly pinned together and to the transparent plate copyboard.

Finally, the cover B is closed down over sheets pinned to the plaque and the latch 36 engaged. The resilience of the conductive pad 34 by way of shear ac-

tion presses out any wrinkles at the laminate interfaces so as to secure efficient distribution of electrostatic charges at such interfaces and by way of compressive action brings the charges at such interfaces into intimate proximity so as to optimize electrostatic adhesion.

In turn, the attractive forces of the electrical charges pull downward on the pad 34 reinforcing because of the resilience of the pad, the physical pressure it can exert. Additionally, the conductive pad 34 allows continuous replenishment of charges lost by leakage from the system.

While only a single negative 30 is shown in the drawing, it is to be noted that a plurality of overlying negatives may be employed as when a composite pattern is to be embodied on the film 28. In the latter case, each negative is pinned to the underlying negative in a manner identical to that described above in relation to the film 28.

Although this invention has been described in considerable detail, such description is intended as being illustrative rather than limiting, since the invention may be variously embodied without departing from the spirit thereof, and the scope of the invention is to be determined as claimed.

What is claimed is:

1. Contact printing apparatus comprising:
a transparent plate of insulating material having first and second surfaces and including a transparent electrode of electrically conductive material in contact with and substantially covering the first surface thereof,
means for applying a D.C. high voltage with respect to ground on said transparent electrode,
means for directing light through said transparent electrode and said transparent plate,
a rigid cover for movement toward the second surface of said transparent plate,
a conductive pad of compressively yielding material on said cover for resilient surface-to-surface contact with abutting sheets of material electrostatically laminated to the second surface of said transparent plate, and
means for connecting said pad to ground, whereby pressing said conductive pad against the sheets electrostatically laminated to the transparent plate will increase the electrostatic force holding the sheets together and to the surface of said transparent plate and provide wrinkle-free flat disposition preparatory to exposure of the laminate to light.
2. The apparatus of claim 1 wherein said conductive pad comprises a sponge-like elastomer.
